(57) **CLAIM**

The ornamental design for a magnetic disc storage unit for electronic computer, as shown and described.

DESCRIPTION

FIG. 1 is a front, top and right side perspective view of a magnetic disk storage unit for electronic computer showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an enlarged view of the portion identified in FIG. 2 by the section “A-A” and “B-B” shown separately to more clearly illustrate the gridded portion.

The broken line showings in FIG. 7 are included for the purpose of illustrating portions of the magnetic disk storage unit for electronic computer and form no part of the claimed design.
